(57) CLAIM

The ornamental design for a pet bed with tent as shown and described.

DESCRIPTION

FIG. 1 is a front view of a pet bed with tent according to my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is an enlarged view of area C indicated in FIG. 3. The dash-dot broken lines illustrate the bounds of the enlarged views and form no part of the claimed design.

1 Claim, 8 Drawing Sheets
